UNITED STATES PATENT OFFICE.

BENJAMIN R. HAWLEY, OF CHICAGO, ILLINOIS, ASSIGNOR TO AGNES HAWLEY, OF SAME PLACE.

HEATING SYSTEM.

SPECIFICATION forming part of Letters Patent No. 258,918, dated June 6, 1882.

Application filed December 27, 1881. (No model.)

To all whom it may concern:

Be it known that I, BENJAMIN R. HAWLEY, of Chicago, Cook county, State of Illinois, have invented certain new and useful Improvements 5 in Heating Systems, of which the following is a specification.

This invention relates to improvements in the endless hot-air-pipe heating system patented to me on the 27th of September, 1881, 10 and is designed to increase the speed with which the air travels its endless path through the pipes, heater, and radiator, and otherwise to increase the efficiency of this and similar apparatus.

15 The main feature of my improvement consists in passing the return air-pipes—viz., the pipes which conduct the air from the radiators back to the heater—through cold-air ducts, whereby said return-pipes and the air passing 20 through them are chilled and a greater difference in temperature is obtained between the air flowing from and that returning to the heater than is obtained by the construction disclosed in my said patent. As the air circulates in this apparatus in obedience to natural 25 laws, the warm air rising and the cold air falling, and as the hotter the hot air is the faster it will rise, and the colder the cold air is the more rapidly it will fall, it follows that the 30 greater this difference in temperature the more speedily will the air circulate. This is a desirable result, as the amount of heat carried to the radiators depends in large measure upon the rapidity with which the air moves through 35 the pipes.

There are other features of utility in my apparatus which will now be explained, reference being had to the accompanying drawing, which shows a section of a dwelling-house to which 40 my previous and present improvements have been applied.

In said drawing, A represents the fire-chamber of a furnace, and A' the jacket surrounding the same, leaving the heating-chamber A² between them, said heating-chamber forming part of the endless system heretofore patented. From this heating-chamber hot-air pipes B lead upward to the radiators C and C', of 45 which the former is located in a box under the 50 floor of the room, so as to warm by indirect ra-

diation, and the latter is placed in the room, so as to give out direct heat. These radiators are composed of exterior jackets, c, and vertical pipes c', extending through the same, whereby to increase the radiating-surface. The hot-air pipes open into the upper portion of the chamber formed by the jacket c, and the return-pipes B' draw off the air from the lower portion of the same, as clearly indicated. The radiator C' is supported upon a perforated base, 60 c², to give the air access to the under end of the pipes c'. The pipes B' draw the air away from the radiators and lead it down to the heating-chamber A². They may be located in boxes or passages B², and some portion of them 65 should be exposed in a cold-air duct, D, which is open to the outside air. This will chill said pipes B' and hasten the fall of the air therein, as already explained. This effect may be increased by connecting the passages B² with 70 said cold-air duct, as shown in the case of the return-pipe from the radiator C; and this enables the accomplishment of an additional desirable result—viz., the admission to said radiator of pure fresh air, which is warmed thereby, 75 and is thence sent into the room for respiration. If this latter feature were used with the other radiator, C', then said radiator would heat by both direct and indirect radiation, as is obvious.

80 The smoke and products of combustion are led from the furnace through a radiator, E, much like those already described, being discharged into the upper portion thereof and drawn off from the lower part thereof into the 85 chimney E'. This radiator is inclosed in a box, E², which is supplied with air from the cold-duct D by a passage, e, and said air, after passing around and through the tubes c' of said radiator, is given exit into the room above by 90 the passage e'. By this arrangement but little heat is wasted through the chimney, and the room may be pleasantly warmed by fresh air not overheated.

In addition to the beneficial effect mentioned, gained by passing the return-pipes through the cold-air duct, it may be added that the fresh air in said duct is partially warmed by contact with said pipes, and hence requires less heat from the radiators to bring it to the 95 100

necessary temperature for respiration; also, that the cooler the air is when returned to the heater the more heat it carries away with it, so that the furnace, which may be located where little warmth is desired, may be kept less hot than it otherwise would be, and without impairing the efficiency of the radiators.

In order that the drawing may be easily understood, I have used arrows to denote the course and character of the various currents, as follows: The arrows with plain stems indicate cold air from the outside, those with a circle upon the stem the warm air from the radiators, those with a cross the hot air rising from the heater to the radiators, those with dotted stems the cooled air returning from the radiator to the heater, and the feathered stems the smoke and products of combustion.

I am aware that the return-pipes have been passed across a narrow warming-space exterior to the ordinary heating-chamber surrounding a furnace, and intended to bring the air in said warming-space to the proper temperature for respiration; also, that return-pipes 20 taking the air from the floor of the room have

opened into cold-air ducts, mingling their air with that of the ducts; also, that return-pipes have been employed to conduct the air from the floor of the rooms to heating-radiators, which delivered it again to the rooms at the upper part thereof. For obvious reasons none of these systems embrace my invention.

Having thus fully described my invention, what I claim, and desire to secure by Letters Patent, is—

1. The combination of the return-pipe with the cold-air duct, through which it passes without opening thereto, whereby the return-pipe is subjected to the cooling effect of the outside atmosphere before the latter becomes 30 warmed, substantially as specified.

2. The combination, with the return-pipes, the radiators, and the cold-air duct, of the passages surrounding the return-pipes and connecting the cold-air duct with the radiator, substantially as set forth.

B. R. HAWLEY.
